UNITED STATES PATENT OFFICE.

FRANK HOFFMAN, OF BUFFALO, NEW YORK.

WOODWORKING MACHINE.

Application filed September 23, 1925. Serial No. 58,073.

This invention relates to woodworking machines of the shaper type which are used for the purposes of cutting rabbets, grooves, or recesses in wood or the like.

- 5 An object of the invention is to provide an improved woodworking machine of the shaper type which may be employed for cutting grooves in different widths of pieces without adjustment or changes in the machines within certain limits, with which a maximum number of different widths of strips may be worked upon without changes in any adjustments and which will be relatively simple, effective and inexpensive.
- 10 Objects of this invention are to provide a cutter head for use on machines of the kind described, and which is provided with a part for supporting the cutters or knives, and with another part which serves to guide 20 the work which is being cut; also to provide a cutter head of this kind which may be used with or against the grain and which may be used without guides or jacks on the table of the machine so that a single cutter 25 head may be employed for cutting rabbets or the like, regardless of whether the work is curved or straight, and regardless of the direction of the grain in the work; also to improve the construction of cutter heads 30 in other respects hereinafter specified.

In the accompanying drawings,

Fig. 1 is a top plan view of a cutter head, showing the same arranged above the table of a woodworking machine.

35 Fig. 2 is a sectional elevation thereof on line 2-2, Fig. 1.

Fig. 3 is a fragmentary section thereof on line 3-3, Fig. 1.

40 Woodworking machines of the shaper type are ordinarily provided with a pair of vertical arbors or shafts revolving in opposite directions and each of these arbors carries a plurality of cutters arranged on edge and which are clamped between grooved plates or disks. The tables of such 45 woodworking machines are also provided with a number of guides or jacks by means of which the work to be cut is held in correct relation to the cutter heads, and when 50 an operative is working on a piece of wood on a table of this kind, it is necessary to carefully watch the grain and if the grain changes it is necessary to change the work from one cutter head to the other so that 55 the cut is always made with the grain as

otherwise the cutters will tear into the wood and spoil the work because there is no part associated with the cutters to limit the depth of cut, and the continuous, relatively broad edges of the knives dig deeply into the wood when working against the grain. By means of my invention the need for two cutter heads revolving in opposite directions is eliminated and also the guides or jacks usually employed for holding the work in correct relation to the cutter heads can be eliminated.

60 The accompanying drawings show, by way of example, one embodiment of my invention, and show a portion of a table A of a 70 woodworking or shaping machine as now commonly used, which table is provided with the usual circular aperture or hole a therein, Fig. 2, in which the cutter head operates, and B represents the usual arbor or up- 75 right shaft on which the cutter head may be mounted. All of these parts have heretofore been employed in connection with 80 woodworking machines of the kind specified and of themselves constitute no part of my 85 invention.

My improved shaper cutter head includes a substantially disk shaped face or radial portion C provided with a central hub c having a bore through which a part of the arbor B may extend and the cutter head may be clamped on the arbor in any suitable or desired manner. In the particular construction shown a collar b is provided which fits against a shouldered portion of the arbor B 90 and engages the lower end of the hub c of the cutter head, and another collar b' is arranged above the cutter head. A nut b² may engage the threaded upper end of the arbor B and thus clamp the cutter head in place 95 on the arbor, a sleeve b³ being inserted between the nut b² and the collar b' in the construction shown. Any other means may, however, be provided for securing the cutter head on the arbor B.

100 The face portion C of the cutter head terminates in an annular, downwardly extending flange D, which may fit into the hole or aperture a in the table A of the wood-working machine, and the outer surface of which is substantially smooth and unbroken, and may be polished, and serves as a guide for the work X, Fig. 1, as will be herein-after more fully explained.

105 The knives or cutters are mounted on the 110

cutter head in such a manner as to extend outwardly beyond the outer flange D, and in the particular construction illustrated, the upper face C of the cutter head is constructed so as to support the cutting knives or tools thereon, and for this purpose the upper face of the plate C of the cutter head is provided with a plurality of ribs or projections E extending above the surface of the plate C and against each of which an edge of a cutting knife F may be placed. The cutting knife F may be held in place on the cutter head by any suitable means, such for example as bolts G, the lower ends of which are suitably secured in the cutter head and the upper ends of which are provided with nuts g which may be clamped against the upper face of the cutters or knives F. Each bolt, in the construction shown, extends through a longitudinal slot g' of the knife or cutter F, which makes it possible to adjust the knives or cutters F radially with reference to the cutter head. Any other means for securing the cutters to the cutter head may, of course, be employed without departing from this invention, those shown, however, being of simple and reliable construction and permit the cutters to be removed and replaced by other cutters, and adjusted to produce the desired depth of cut, with very little loss of time.

The cutters F are of the saw toothed type, having a plurality of teeth or cutting edges f, the points of which are disposed concentrically with reference to the axis of the cutter head. Such cutter can be used in cutting either with or against the grain of the wood or other material being cut for the reason that the ends of the teeth of each cutter will successively bite into the wood, making only relatively small cuts. In the use of this machine it will be understood that the arbor B may be raised or lowered to position the knives or cutters F at the desired elevation above the table. The work X is then placed on the table and pressed against the outer face of the smooth flange D of the cutter head, and the work may be moved lengthwise along the table and relatively to the flange D of the cutter head until the desired cut has been made. Furthermore, with a cutter head of this kind used on a shaping machine, a number of spaced or different cuts may be formed at different places along a piece of work, by moving the work into and out of engagement with the flange D as the work is advanced past the cutter head. In the particular construction shown in the drawings, a pin or roller H is shown on Fig. 1, which may be inserted in any one of the series of holes h in the table and against which the back of the work X may be pressed so that the work can be pressed against the flange D of the cutter head with better leverage.

The work can then be moved lengthwise relatively to the cutter to have the desired cutting operation performed thereon regardless of whether the cut is being made with or against the grain. Consequently only one cutter head is required, and any work may be cut, regardless of its shape or curvature, and the use of guides for holding the work relatively to the cutter is eliminated. The depth of the cut may be readily controlled by adjusting the knives F toward and from the axis of the mandrel, and the width of the cut can be controlled either by raising or lowering the mandrel, so that a wider cut can be made by moving the work past the cutter two or more times, or if desired wider cutters or knives F may be employed. The shape of the knives F may, of course, be varied to suit the cut desired. The cutter head described is particularly desirable for use on work having various kinds of curves, since the cutter head can be used effectively on any kind of curves excepting concave curves of a smaller radius of curvature than that of the cutter head itself, whereas with shaper machines heretofore made employing jacks or guides for holding the work in correct relation to the cutter head, the cutting of irregular curved edges was extremely difficult and in many cases impossible. Since no attention need be paid to the grain of the wood, satisfactory work can be accomplished by inexperienced mechanics, and the speed of operations on work is greatly increased by means of my improved cutter head since all of the work can be done on one cutter head, thus eliminating the time heretofore required in changing over from one cutter head to another.

The cutter head described also has the advantage that it can be easily set up or assembled for the particular work to be done. If the cutters or knives are to be removed and replaced by others, it is only necessary to remove the units g from the bolts G, then to remove the cutters and place the others in position, the depth of the cut to be made being controlled by the distance to which the cutters or knives extend beyond the flange D.

I claim as my invention:—

1. A cutter head for shaper machines having a radially extending face portion, an annular peripheral flange extending around said face portion, a plurality of ribs extending upwardly from said face portion and forming stops, saw toothed cutters adapted to be secured to said face portion and arranged against said stops with their saw toothed portions projecting beyond said flange, and adjustable securing means for holding said cutters against said stops and for positioning said cutters for determining the depth of the cut to be made by the extent to which said cutters project beyond

said flange, said flange forming a smooth, continuous guiding surface against which the work to be cut is pressed.

2. A cutter head for shaper machines having a radially extending face portion, an annular peripheral flange extending around said face portion, saw toothed cutters adapted to be secured to said face portion with their saw toothed portions projecting beyond said flange, substantially radially extending stops on said radially extending face

portion against which a side of each cutter is adapted to bear, and adjustable securing means for holding said cutters against said stops for positioning said cutters for determining the depth of the cut to be made by the extent to which said cutters project beyond said flange, said flange forming a smooth continuous guiding surface against which the work to be cut is pressed. 15

FRANK HOFFMAN.
